ALBERT V. J. IRELAND, OF NEW YORK, N. Y.

STILETTO OR POINTED PIN.

1,161,684.

Specification of Letters Patent. Patented Nov. 23, 1915.

Application filed February 23, 1915. Serial No. 10,106.

To all whom it may concern:

Be it known that I, ALBERT V. J. IRELAND, a citizen of the United States, residing at Corona, city of New York, in the county of 5 Queens and State of New York, have invented a new and useful Stiletto or Pointed Pin with an Adjustable Gage Attached for Piercing Holes into Material to be Embroidered Upon.

10 My invention relates to stilettos or pointed pins having a gage, for piercing different sized holes and the object of my improvement in such device is—to consist of the least number of parts, making the setting of the 15 gage for holes of different size as easy and convenient as possible, and to puncture the material and spreading the mesh of same without destroying said material. I obtain these objects by a stiletto or pointed pin constructed as fully illustrated in the accompanying drawing, in which—

Figure 1 is a general view of the stiletto or pointed pin, and its application upon the material to be embroidered, stretched and 25 held within the ordinary embroidery hoops or frames marked 11. Fig. 2 is a view taken from right hand side Fig. 1, and is partly in section to show notches or stopping grooves of the gage to set same for desired 30 sized hole and to prevent shifting of the gage (marked 12) without aid of any set screws or clamping device. Fig. 3 is a cross section through gage or friction sleeve 12. Fig. 4 is an enlarged front view of the 35 stiletto or pointed pin, similar to Fig. 1, but with gage 12 shown moved forward, exposing to view the notches marked 8, 7 and 6. Fig. 5 is also an enlarged side view of Fig. 4, and partial section on line 5—5 of 40 Fig. 4, to more clearly show the engagement of small tongues 13 of gage 12, with the notches in pin 15, and which engagement positively prevents shifting of the gage, or 45 stopping sleeve 12 farther away from pointed end of pin 15, insuring the piercing of holes of the size set. Fig. 6 is a cross section on line 6—6 of Fig. 4, showing more clearly how pin 15 is encircled and gripped under desirable elastic or spring 50 pressure of the sleeve or gage 12 formed from a flat band of springy material. Fig. 7 is a side view of the stiletto or pointed pin with gage or sleeve 12 partly in section and radially turned upon the pin 15, dis- 55 engaged from the notches by turning upon the smooth straight surface of the pin and

shown as shifted forward under slight elastic friction of the sleeve 12, so as to cover and protect the pointed end 16 of pin 15. Fig. 8 is a section through flattened portion 60 of pin on line 8—8 of Fig. 4.

Similar numerals refer to similar parts throughout the several views.

As seen from drawing this stiletto or pointed pin consists of two simple parts 65 only; a pointed pin 15, notched upon its cylindrical surface and made of any hard suitable material, as metal, celluloid, bone or wood, &c. and a frictionally sliding sleeve, made from elastic material or sheet, as 70 metal, celluloid, &c. shaped to encircle the piercing pin 15, with desirable elastic or springy grip, to prevent its falling off, and with sufficient spring friction to permit, (if desired) the piercing of smaller size holes in 75 less resisting thinner material, even without the turning of the sleeve or gage 12 with its tongues 13 into engagement of notches marked 1 to and including 8, indicating size of holes. The setting and turning of the gage 12 by the finger flange 17 80 into the proper notch, corresponding to size of holes to be pierced, becomes necessary in piercing larger holes or for more resisting or thicker material to insure positively 85 against any shifting and change of holes. For the usual embroidery or needlework this piercing pin 15 is about $1/4''$ diameter, 4 to 5 inches long with a pointed end 16 about $1''$ long with notches about $1/8''$ apart 90 and numbered 1—2—3 to and including mark 8, so that for gaging and setting the size of hole pierceable by the setting, is by 95 this stiletto or pointed pin indicated by the lowest number exposed by the gage 12, as for example and as shown in Fig. 4, where the lowest number exposed or opened to view is shown as 6, it would, under the said proportions, indicate that the setting at 6 shown in Fig. 4, a hole of $6/32''$ could be 100 pierced, while if gage would be set that only number 1 notch would appear outside of gage, then a hole of only $1/32''$ could be pierced, or at any setting just as many $1/32''$ of one inch diameter holes as the lowest number exposed by the gage indicates. 105

The end opposite to the tapered or pointed end of pin 15 may be shaped or formed differently to suit tastes, and is not affecting the principal features, therefore only 110 two of many possible forms of end are shown as in Figs. 1 and 4, rounded and grooved,

and as in Fig. 7 formed as a rounded eyelet 19. The pin may or may not be flattened: flattened as at 20, Figs. 1, 2, 4 and 8, to afford a firm grip in twisting or changing 5 the gage.

The gage, or frictional sleeve 12, is a band or ribbon of suitable outline and material, formed to encircle the pin 15, with desired elastic grip upon the piercing pin, and is 10 provided in one piece, with one or more tongues 13 of semicircular or other suitable shape or form, and being directed inwardly and at same distance apart, so that all 15 tongues of the gage come in contact and proper engagement with the resisting faces of the notches in the pin 15, so as to positively hold gage to pin against the highest resistance of piercing heavy or tough material. To reduce size of holes from larger 20 hole setting, the gage needs only to be shifted toward the pointed end 16 of pin 15, as the tongues 13 will not be resisted in the movement of gage toward the tapered end, because the notch surfaces in this direction 25 are slanting, tending to lift the tongues like pawls over the slant or incline under the assistance of the springy, yielding and slightly opening gage 12. But to increase size of hole from smaller settings the flange 30 17 is to be pressed in the direction 18 with the effect that the tongues hindering movement of gage from pointed end of pin become, by indicated turn of 1/4 revolution, 35 disengaged from notches and brought upon the smooth surface of the pin as clearly shown in Fig. 7, in which position of the gage movement from or to pointed end of pin is made equally easy, while further turning of the gage into engagement with 40 notches will then prevent sliding of gage under any resistance against piercing any size or number of holes. This gage 12 may or may not be provided with a front flange 21 to enlarge the stopping surface of the 45 gage, to prevent damage to delicate embroidery materials.

As this improved stiletto or pointed pin has only two parts which are held together under spring friction and by notches, and

does not require set screws or other little 50 parts to be fastened and loosened, it is to be considered as another improvement and advantage, that by this construction, no parts can be lost as in some other stilettos, and that the piercing point becomes quickly 55 shielded after use by simply pushing the gage or sleeve 12 forward to cover the same as shown in Fig. 7.

I am aware that prior to my invention stilettos have been made with gages attached, I therefore do not claim broadly: but I claim—

1. A stiletto or pointed pin provided with stop notches, and an encircling sleeve with pawls or tongues to engage the sleeve against 60 backward shifting, and so constructed as to permit forward shifting without necessity of turning or rotating, but permitting backward shifting for change of hole-punching diameter, only by partial turn of the 65 sleeve to disengage from the stopping tongues and notches.

2. A stiletto or pointed pin with notches or rack in combination with a sleeve or gage encircling said pin, arranged to permit longitudinal sliding without necessity of turning; said sleeve having one or more tongues 75 to engage with notches to lock the gaging sleeve at the size of hole desired to be pierced.

3. A stiletto or pointed pin with notches or a rack in combination with a sleeve or gage encircling said pin with elastic or spring pressure grip permitting longitudinal shifting without turning and having 85 tongues or pawls to engage with and against notches or the rack of the pointed pin.

4. A stiletto or pointed pin with notches or rack in combination with a sleeve having a stop flange at the front and a side flange 90 at its side and encircling the pin with inward spring pressure permitting sliding and provided with tongues or pawls engaging with the notches or rack of pointed pin.

ALBERT V. J. IRELAND.
